WILLIAM H. PAGE, OF NORWICH, CONNECTICUT, ASSIGNOR TO WILLIAM H. PAGE & CO.

Design No. 3,902, dated March 15, 1870.

DESIGN FOR TYPE.

The Schedule referred to in these Letters Patent and making part of the same.

To all whom it may concern:

Be it known that I, WILLIAM H. PAGE, of the town of Norwich, in the county of New London, and State of Connecticut, have invented or produced a new and original Design of Letters for Printing Purposes, styled "Double-Gothic," for letter-press printing; and I do hereby declare that the accompanying drawing is a full and exact representation of the same.

The letter may be printed either with or without the shade, or the shade printed in a different color.

What I claim as new, and desire to secure by Letters Patent, is—

The design for an alphabet of letters, as shown and described.

WM. H. PAGE.
